CLAIM

We claim the ornamental design for an architectural panel with millet and grass, as shown and described.

DESCRIPTION

FIG. 1 is a perspective view of an architectural panel with millet and grass, showing our new design

FIG. 2 is a front view of the architectural panel with millet and grass.

FIG. 3 is a left side view of the architectural panel with millet and grass

FIG. 4 is a right side view of the architectural panel with millet and grass

FIG. 5 is a top view of the architectural panel with millet and grass; and

FIG. 6 is a bottom view of the architectural panel with millet and grass.

The back view is unornamented and not shown.

The broken lines in the drawings depict environmental subject matter only and form no part of the claimed design.
